JOSEPH M. BACIGALUPI, OF OAKLAND, CALIFORNIA, ASSIGNOR TO MERCHANT CALCULATING MACHINE COMPANY, A CORPORATION OF CALIFORNIA

WORK FEEDING DEVICE

Application filed January 15, 1930. Serial No. 420,887.

The present invention relates to metal working machinery and particularly to feeding fingers adapted for use in automatic screw machines, forming or cutting-off machines, and the like.

5 An object of the invention is to provide a bipartite stock feeding device in which the stock gripping function is performed by a readily replaceable member of nominal cost, and sized to accommodate the stock to be used.

10 Another object of the invention is to provide a bipartite stock feeding device in which the stock gripping function is performed by a replaceable member of relatively soft material, incapable of scratching polished stock, while the necessary resiliency for gripping is provided by a second element capable of receiving and retaining sufficient temper.

15 Another object of the invention is to provide a stock feeding device in which the tempered portion thereof is sufficiently insulated from frictionally induced heat to permit retention of its temper.

20 Another object of the invention is to provide a stock feeding device in which the part subject to deterioration is capable of replacement at a nominal cost.

25 Another object of the invention is to provide a device of the above attributes or any of them which may be incorporated in modern standard machines without modification of the machine.

30 Other objects will appear as the description progresses, reference being had to the accompanying drawing in which:

Figure 1 is an elevation of the auxiliary feeding finger.

35 Figure 2 shows the auxiliary feeding finger inserted in a standard feeding finger and under the compressive spring action of the latter.

40 Figure 3 is a longitudinal section through the feeding finger assembly and a part of the

feed tube illustrating the manner in which the stock is gripped.

The form of construction selected for illustration in the present application will be rather specifically described, but it is to be understood at the outset, that within the scope of the invention as claimed, variations may be made.

45 In the present type of automatic metal working machines, great difficulty has been experienced in finding some satisfactory means of feeding polished stock without scoring and scratching the same. The standard feeding fingers now employed are usually made of steel, and comprise a hollow tubular body member which is threaded at one end for attachment to the stock bar feed tube, while the other end is slotted, slightly tapered, and spring tempered to create a strong compressive or clamping action.

50 Steel, however, has a strong abrasive action on the stock, and when brought into frictional engagement with other stock, has the tendency to mark the latter, especially when, as is frequently the case, burrs are left in the feeding surfaces by the manufacturer. Therefore, when the feed finger is moved rearwardly over the stock preparatory to gripping and pushing the stock bar forwardly, the latter is badly scored.

55 The only way to overcome this condition, when feeding polished stock, has been to lap the fingers out at certain intervals to maintain an absolutely smooth gripping surface. This procedure, however, caused the fingers to wear down much faster and therefore loose their gripping action, resulting in slippage and inaccurate feeding.

60 The manufacturers then tried using softer materials such as bronze in the feeding fingers, but this method also proved unsatisfactory due to the fact that such metals could not be tempered to provide the necessary spring tension to clamp and feed the stock accurately a predetermined distance. It was

also found that feeding fingers made of bronze would only last a very short time, necessitating replacements much more often than steel.

5 Other means have been tried to overcome these great disadvantages in feeding means for polished stock bar, but none seem to have proved successful, mainly for the reason that the improvements required a change in the 10 feeding finger or machine as supplied by the manufacturers with the result that the manufacturer could not avail himself of this improvement without changing the feeding mechanism entirely, or else increasing the 15 sizes and diameter of the entire feeding mechanism, including feed tube, collet, and spindle.

With these drawbacks of prior structures in mind, the present invention contemplates 20 as shown in the drawing, a simple and inexpensive auxiliary feeding finger which can be easily inserted in the standard feed mechanism as supplied by the manufacturer.

Referring to the drawing which clearly illustrates 25 the auxiliary feeding finger, it can be seen that it comprises a tubular body member 10 which is formed out of a solid round bar of bronze, or similar material, by drilling a central bore 11. It is then counterbored to 30 about three quarters of its length, with the result that the tubular member 10 has a substantially thicker wall 12 at one end thereof, this end being selected to provide the smooth gripping or clamping surface 13 35 which must conform to the shape of the stock bar to be fed. In the present instance, a round bar is illustrated and hence the surface 13 is annular to correspond to the stock.

This tubular member 10, which constitutes 40 my auxiliary feeding finger, is then turned down on the outside to provide at the other end a narrow shoulder or flange 14, after which it is slotted to approximately its center, starting at the end which carries the 45 gripping surface 13. The slots 15, created by this slotting operation, give this part of the feeding finger the necessary flexibility to permit it to be compressed upon the stock by the resilient fingers 20 of the main feed finger. Apertures 16 are also provided in the 50 opposite end of the auxiliary feeding finger, so that when the latter is inserted into the standard feeding finger 17 (Figures 2 and 3), these apertures 16, as well as the slots 15, may 55 be aligned with those with which the standard feeding finger 17 is equipped. The outer surface of tubular member 10, of course, conforms to the inside bore of the standard feeding finger 17, as can be readily observed from 60 the drawing. The feeding finger 17 which is standard equipment of every feeding mechanism for automatic screw machines, etc., needs no further description other than that it is made of some good grade of steel tubing, has a threaded portion 18 at the end by

which it is attached to the feed tube 19 (Figure 3). The other end 20 is slotted exactly like member 10 and is spring tempered, as is well known. Apertures 21 diametrically opposed are provided to allow insertion of a turn key for screwing the feeding finger onto the feed tube 19.

In practice, when it is desired to work polished stock, the standard feed finger 17 is removed from the feed tube 19 and the auxiliary feeding finger 10 is inserted manually until shoulder 14 abuts the end of the threaded portion 18 of finger 17. The assembled unit is then screwed into the feed tube 19 by means of a suitable key until the other end of the shoulder 14 of the auxiliary feeding finger 9 is forced against the offset 22 formed within the feed tube 19 by the internal thread 23, thus creating an extremely simple and efficient union between the feeding fingers 85 and tube.

The auxiliary feeding finger is securely locked against longitudinal movement within the assembled feed unit, and the spring action of the main feeding finger is imparted to the inserted one which therefore is in condition to grip the work stock with sufficient pressure to assure accurate feeding of the stock at predetermined intervals, regardless of slight variations in the size of the stock.

When the auxiliary feed finger becomes worn by the passage of stock therethrough, it may be easily replaced at nominal cost. The main feed finger, being relieved of all wear, and sufficiently insulated from frictionally induced heat by the interposed auxiliary finger, will last indefinitely.

I claim:

1. A work feeding device comprising a stock feeding member, a feed tube having 10 means for securing said member thereon, an adapter insertible into said member, and means for maintaining said adapter in proper working relation with said member comprising shoulders on said member and said tube adapted to grip said adapter.

2. A work feeding device comprising a member having a plurality of fingers, an adapter insertible therein provided with a plurality of fingers, a feed tube provided with means for securing said member thereto, means for aligning said member and said adapter during attachment to said tube comprising aligned apertures in said member and said adapter adapted to receive a key, and means for retaining said member and said adapter in alignment after attachment to said tube comprising shoulders on said member and said tube adapted to grip said adapter.

3. A work feeding device comprising a stock feeding member having a plurality of fingers, a feed tube provided with means for securing said member thereto, an adapter insertible within said member, and means for

preventing longitudinal movement of the adapter with respect to said member and said tube comprising shoulders formed on said adapter and adapted to cooperate with shoulders on said member and said tube.

4. A work feeding device comprising a stock feeding member, an adapter insertible within said member, said adapter and said member having shoulders formed thereon to limit the movement of said adapter upon insertion within said member, and a feed tube provided with means for securing said member thereto and a shoulder for holding said adapter within said member in assembled position.

JOSEPH M. BACIGALUPI.
